UNITED STATES PATENT OFFICE.

PETER PARKE, OF CHICAGO, ILLINOIS, ASSIGNOR TO THE PULLMAN COMPANY, OF CHICAGO, ILLINOIS, A CORPORATION OF ILLINOIS.

WINDOW ARRANGEMENT FOR RAILWAY CARS.

Application filed August 23, 1923. Serial No. 658,969.

To all whom it may concern:

Be it known that I, PETER PARKE, a citizen of the United States, and resident of Chicago, county of Cook, and State of Illinois, have invented certain new and useful Improvements in Window Arrangements for Railway Cars, of which the following is a specification and which are illustrated in the accompanying drawings, forming a part thereof.

This invention relates to railway cars and more particularly to window arrangement thereof, and one of the objects of the invention is the provision of a new and improved window and screen construction and arrangement whereby one of these members is automatically placed in position upon elevating the other.

Another object of the invention is the provision of new and improved means for readily and easily raising and lowering windows of railway cars together with the provision of means for automatically storing the screens associated with said windows when the latter are in lowered position.

A still further object of the invention is the provision of a new and improved window sash provided with a screen and having weather proofing means associated therewith.

Other and further objects and advantages of the invention will appear from the following description taken in connection with the accompanying drawings, in which—

Fig. 1 is a side elevation of a portion of the side wall of the inside of a Pullman or sleeping car, with parts in section and parts broken away;

Fig. 2 is a vertical section on the line 2—2 of Fig. 1;

Fig. 3 is a side elevation of the raising and lowering device;

Fig. 4 is a section on line 4—4 of Fig. 3;

Fig. 5 is a section similar to Fig. 2 but on an enlarged scale, with parts broken away;

Fig. 6 is a section on line 6—6 of Fig. 1, with parts removed;

Figs. 7 and 8 are perspective views of portions of the screen; and

Fig. 9 is a vertical section of a modified form of a screen frame.

For the purpose of simplicity of illustration and convenience in description, the invention is shown as being associated with

the side windows of a Pullman or sleeping car although it is understood it is equally as well adapted to other forms of passenger cars.

On the drawings, the reference character 10 designates a railway car provided with the side wall 11, floor 12 and fixed seats 13 which are arranged facing each other and are adapted to form the lower berth of one of the sections of a sleeper, as is usual in such constructions.

The side wall 11 is provided with window openings 14 in which are mounted the usual window casings provided with guideways 15 for receiving the sashes 16 in the usual manner. The inwardly extending portion 17 of what may be termed the sill is provided with an upstanding flange 18.

Each sash 16 has its lower rail 19 rabbeted at its lower portion to form the recess 20 and the lip, lap or projecting portion 21 which is adapted to engage over the flange 18 to form a weather tight joint. The recess 20 may be and preferably is stepped to form the ledge 20', Fig. 5, to form an abutment for the screen as will presently appear. Suitable weather striping 22 may be secured to the under side of the lower rail 19 for excluding the weather and for supporting the window when it is in lowered position.

It is desirable that suitable mechanism be employed for mechanically opening and closing the windows. It is also desirable that the window screens be automatically moved to operative position simultaneously with the opening of the windows and be moved to their concealed or storage position when the windows are closed. Any suitable mechanism may be employed for this purpose. In the form of the device selected to illustrate the invention, the sash 16 are arranged to slide vertically and each sash is provided with a screen 23 which is adapted to be raised and lowered with the sash. While the screen 23 is shown as being mounted in a frame separate from the window sash 16, it is evidently immaterial so far as the raising and lowering of the window is concerned whether the screen is separate from, attached to, or integral with the window sash 16. In the form selected to illustrate one embodiment of the invention, however, the screen is separate and detached from the window sash but it may be other-

wise. As shown, each screen preferably, although not necessarily, comprises two parts—a support 24 and a frame 25, the latter being covered with reticulated or 5 foraminous material as the screen wire or member 26.

The frame 25 is detachably mounted in the support 24 in any suitable manner. As shown, the lower portion of the frame 25 is 10 provided with a recess or channel 27 which is adapted to engage or interlock with a bead 28 on the support 24 for holding the lower portion of the frame in position within the support. The upper portion of the frame 15 is provided with spring pressed catches 29 which are adapted to engage in the elongated recess 30 in the upper portion of the support 24.

Suitable raising and lowering mechanism 20 are associated with each screen. As shown, this mechanism comprises a supporting plate 31 on which are mounted the shafts 32 and 32^a carrying the sprockets 33 and 34 for operating the sprocket chain 35. The chain 25 is provided with a laterally extending headed pin 36 which is adapted to engage the horizontal portion of the slot 37 in the extension 38 on the support 24. The pin 36 is attached to the support 24 by passing 30 the same through the vertical portion of said slot.

The chain is operated by the handle 39 through a suitable train of gears 40 and 41 in the usual manner. In order to maintain 35 the chain 35 taut at all times the lower sprocket 34 may be mounted on a spring pressed block 42.

The plate containing the operating mechanism is preferably removably secured in 40 operative position. As shown, the lower edge of the plate 31 is first placed in position in the channel 43 after which the upper end of the plate is moved to position in engagement with the ledge 44 and secured thereto 45 by suitable fastening means as the screws 45. A finishing panel 46 with suitable upholstery is adapted to be secured in position adjacent the seat to conceal the plate carrying the operating mechanism. The panel 46 50 is provided with a recess 47 in which the operating handle 39 is located in order that the same may not project beyond the surface of said panel.

The handle 39 is mounted on and carried 55 by the panel 46 in such a position that it will be adjacent the seat readily accessible to the occupant of said seat. The stem 56 of the handle 39 is provided with a reduced portion 57 which is journaled in a bearing 58 60 carried by the panel 46. The stem 56 is provided with a polygonal bore which is adapted to engage a corresponding projection on the shaft 59 when the panel 46 is placed in position. The friction of the parts together 65 with the pressure of the seat cushion will

hold the panel 46 in position without the necessity of additional fastening means.

A suitable recess 48 is provided above each window opening for receiving the upper portion of the corresponding window when it is in open or elevated position, and a recess 48^a below each window is adapted to conceal the screen when the window is in lowered or closed position.

A tubular member 49 in communication 75 with the bottom of the recess 48^a extends to a point beneath the car whereby water and other foreign substances finding their way into the pocket or recess when the sash is 80 raised may escape therefrom.

When the screen is in position beneath the sash the support is adapted to be in engagement with the ledge 20^a and when the sash is in lowered position the flange 18 engages 85 between said support and the lip or projecting portion 21 of the sash thereby forming an effective joint for excluding rain and the like.

It is immaterial, so far as the operation of the device is concerned, whether or not the screen is actually secured to the sash. As shown, the screen merely engages the sash but is not secured thereto. In the operation of the device the raising of the screen will also raise the sash and will support the same 95 in any adjusted position. When the mechanism is operated to lower the screen the weight of the sash will cause the same to follow the screen in its downward movement. When in lowered position the sash is supported in the usual manner on the window sill.

Passenger cars are usually provided with double windows to form an air space between the two in order to prevent frosting of the panes during cold weather, and at the same time to provide an insulation to prevent escape of heat from the car. Since the sashes must be mounted so they can be raised and lowered it is impossible to make the construction dust-proof and consequently it is at times necessary to clean the inner sides of the sashes. This is a more or less difficult task, and especially so in sleeping or other cars when upper windows as 54 are employed, due to the fact that the lower sashes cannot be raised sufficiently to permit convenient access to the space between the sashes. In order to overcome this difficulty and at the same time provide a double window a single frame is employed which is provided with the two transparent plates or panes of glass 50 and 51 which are adapted to be permanently secured in the frame in spaced relation to each other. Suitable means such as the cushion members 52 are provided to prevent the entrance of dust between the two panes of glass.

In Fig. 9 there is disclosed a modified 120 form of screen. In this form of the device 125

the frame 24^a is substantially the same as the corresponding frame 24 in Fig. 5, except that the sheet of reticulated or foraminous material is located on the inner side 5 of the frame and the frame is provided with baffle plates or louvers 55 extending outwardly and downwardly. This arrangement will prevent the occupants of the car from dropping articles into the recess occupied by the screen when the window is in partially raised position.

The screen assembly disclosed herein is the same as that disclosed and claimed in the application of William C. Smith, S. N. 15 658,951, filed August 23, 1923.

While the means shown for raising and lowering the window and screen comprises an operating mechanism of various movable parts, it is understood that any means of 20 whatever nature may be employed for this purpose.

I claim as my invention:

1. In a car having a sash opening in a side wall thereof, a sash for said opening, a frame beneath said window for supporting the same, means beneath said sash for engaging said frame for raising and lowering said frame, and a screen detachably mounted in said frame.
2. In combination, a side wall of a car having an opening therein, with a recess below said opening, a sash slidably mounted in said opening, said sash being provided with a rabbet on its lower inner side, a screen engaging said rabbet and adapted to be lowered into said recess and to support said sash when in elevated position, and mechanism engaging said screen for raising and lowering the same.
3. In combination, a side wall of a car having an opening therein, a closure for said opening, a window sill provided with an upwardly extending flange, said closure having a rabbet on its lower portion forming a downwardly extending lip for engaging over said flange and a screen engaging said rabbet for supporting said closure.
4. In combination, a window sill provided with an upstanding flange, a window frame above said sill, said frame being provided with a lip for engaging over said flange and a screen for engaging said sash laterally of said lip for supporting said window in elevated position.
5. In combination with a side wall of a car provided with an opening having an upstanding flange, a window sash having its
- lower portion rabbeted to form a projecting portion, and a screen support for engaging the rabbeted portion of said sash, 60 said flange engaging between said projecting portion and said support when said sash is in lowered position.
6. In combination with the side wall of a car having an opening therein with a recess beneath said opening, a slideable window member for closing said opening, a screen member associated with said window member and adapted to be concealed in said recess, and manually operated means 70 for mechanically simultaneously elevating both of said members.
7. In a car, a fixed seat, a movable sash in the side wall of said car opposite one end of said seat and manually operated means 75 adjacent to said seat for elevating said sash.
8. In a sleeping car provided with a side wall having openings therein, sashes for said openings, seats adjacent to said sashes, a screen beneath one of said sashes and engaging the same, mechanism for raising and lowering said screen to thereby cause the raising and lowering of said sash a supporting plate adapted to be secured to said side wall for supporting said mechanism 80 and a removable finishing panel adjacent to said seats for concealing said supporting plate.
9. In combination with the side wall of a railway car having an opening therein, a 90 window member, a screen member of less thickness than that of the sash of said window member associated with said window member, and means mechanically operated for moving said members.
10. In combination with a car provided with a side wall having an opening therein and a recess beneath said opening, a seat adjacent to said opening, a sash slidably mounted in said opening, means in 100 said recess for moving said sash and a handle member opposite the end of said seat for operating said means.
11. In combination with the side wall of a car having an opening therein, a seat adjacent to said opening, a sash movably mounted in said opening, means adjacent said seat for raising and lowering said sash a panel adjacent to said seat for concealing said means and a handle member 110 carried by said panel for operating said means.

PETER PARKE.

the frame 24^a is substantially the same as the corresponding frame 24 in Fig. 5, except that the sheet of reticulated or foraminous material is located on the inner side of the frame and the frame is provided with baffle plates or louvers 55 extending outwardly and downwardly. This arrangement will prevent the occupants of the car from dropping articles into the recess occupied by the screen when the window is in partially raised position.

The screen assembly disclosed herein is the same as that disclosed and claimed in the application of William C. Smith, S. N. 658,951, filed August 23, 1923.

While the means shown for raising and lowering the window and screen comprises an operating mechanism of various movable parts, it is understood that any means of whatever nature may be employed for this purpose.

I claim as my invention:

1. In a car having a sash opening in a side wall thereof, a sash for said opening, a frame beneath said window for supporting the same, means beneath said sash for engaging said frame for raising and lowering said frame, and a screen detachably mounted in said frame.
2. In combination, a side wall of a car having an opening therein, with a recess below said opening, a sash slidably mounted in said opening, said sash being provided with a rabbet on its lower inner side, a screen engaging said rabbet and adapted to be lowered into said recess and to support said sash when in elevated position, and mechanism engaging said screen for raising and lowering the same.
3. In combination, a side wall of a car having an opening therein, a closure for said opening, a window sill provided with an upwardly extending flange, said closure having a rabbet on its lower portion forming a downwardly extending lip for engaging over said flange and a screen engaging said rabbet for supporting said closure.
4. In combination, a window sill provided with an upstanding flange, a window frame above said sill, said frame being provided with a lip for engaging over said flange and a screen for engaging said sash laterally of said lip for supporting said window in elevated position.
5. In combination with a side wall of a car provided with an opening having an upstanding flange, a window sash having its

lower portion rabbeted to form a projecting portion, and a screen support for engaging the rabbeted portion of said sash, 60 said flange engaging between said projecting portion and said support when said sash is in lowered position.

6. In combination with the side wall of a car having an opening therein with a recess beneath said opening, a slideable window member for closing said opening, a screen member associated with said window member and adapted to be concealed in said recess, and manually operated means 70 for mechanically simultaneously elevating both of said members.

7. In a car, a fixed seat, a movable sash in the side wall of said car opposite one end of said seat and manually operated means 75 adjacent to said seat for elevating said sash.

8. In a sleeping car provided with a side wall having openings therein, sashes for said openings, seats adjacent to said sashes, a screen beneath one of said sashes and engaging the same, mechanism for raising and lowering said screen to thereby cause the raising and lowering of said sash a supporting plate adapted to be secured to said side wall for supporting said mechanism 85 and a removable finishing panel adjacent to said seats for concealing said supporting plate.

9. In combination with the side wall of a railway car having an opening therein, a 90 window member, a screen member of less thickness than that of the sash of said window member associated with said window member, and means mechanically operated for moving said members.

10. In combination with a car provided with a side wall having an opening therein and a recess beneath said opening, a seat adjacent to said opening, a sash 100 slidably mounted in said opening, means in said recess for moving said sash and a handle member opposite the end of said seat for operating said means.

11. In combination with the side wall of a car having an opening therein, a seat adjacent to said opening, a sash movably mounted in said opening, means adjacent said seat for raising and lowering said sash a panel adjacent to said seat for concealing said means and a handle member carried by said panel for operating said means.

PETER PARKE.

Certificate of Correction.

It is hereby certified that in Letters Patent No. 1,541,523, granted June 9, 1925, upon the application of Peter Parke, of Chicago, Illinois, for an improvement in "Window Arrangements for Railway Cars," errors appear in the printed specification requiring correction as follows: Page 1, line 97, for the word "sash" read *sashes*; page 3, line 23, claim 1, for the word "sash" read *window*, and line 25, for the word "window" read *sash*; and that the said Letters Patent should be read with these corrections therein that the same may conform to the record of the case in the Patent Office.

Signed and sealed this 14th day of July, A. D. 1925.

[SEAL.]
